United States Patent Office

Des. 206,981
Patented Feb. 14, 1967

206,981

CIGARETTE SNUFFER

Milton R. Revzin, 727 Delaware Ave.,
Youngstown, Ohio 44510

Filed Apr. 6, 1966, Ser. No. 1,791

Term of patent 7 years

(Cl. D85—2)

FIG. 1 is a top perspective view of a cigarette snuffer showing my new design; and

FIG. 2 is a bottom perspective view from the opposite side.

I claim:

The ornamental design for a cigarette snuffer, as shown.
